BOTTLE CLOSURE

Joseph C. Keaney, Mount Lebanon, and James
M. Guthrie, Pittsburgh, Pa.

Original application July 22, 1936, Serial No.
91,898. Divided and this application January
25, 1937, Serial No. 122,104

5 Claims. (Cl. 215—56)

The invention relates to bottle closures of the sort adapted to safeguard sealed bottles against dangerous internal pressures. The invention, more particularly, consists in a particularly effective embodiment of this known concept in a crown cap.

The application for this patent comprised a division of application Serial No. 91,898, filed July 22, 1936.

10 In the accompanying drawing Fig. I is a view in cross section and on large scale of a conventional form of crown cap, embodying the invention; Figs. II and III, respectively, are views in plan and to smaller scale of a gasket and a diaphragm embodied in the cap; Fig. IV is a fragmentary view of a bottle neck, showing in vertical section the cap assembled therewith; Fig. V is a fragmentary view of the cap, on the plane of section of Fig. I, illustrating a condition of service; and Fig. VI is a view in cross section of a modified form of gasket for use in our cap.

The usual crown closure consists in a shallow cap 1 of sheet metal (ordinarily tin-plate), having a short fluted skirt 2, and including a gasket 3 formed of compressible material, such as cork, secured by means of a thin body or film 4 of adhesive. In service the cap is assembled upon the mouth of a bottle, as illustrated in Fig. IV, the lip of the bottle including a peripheral bead 5, upon which the skirt of the cap is clinched in known way. The gasket is compressed by the cap 1 and secured in gas-sealing position over the mouth of the bottle. Sometimes the gasket is faced with a thin liner disc of impervious material, such as paper impregnated with a substance that is chemically neutral to the contents of the bottle. In recent years aluminum foil coated with a baked coumarone resin has proved successful as a material of which to make such liner discs.

In accordance with the invention, we provide the usually closed disc-like body of gasket 3 with a perforation or recess 3a, and form one or more small perforations 6 in the metal body of the cap 1. Upon the inner or lower surface of the perforate gasket, a liner disc 7 is positioned, and, conveniently, secured by means of adhesive. In the assembly of the cap upon a bottle, as shown in Fig. IV, the periphery of the disc 7 is secured in sealing engagement with the mouth of the bottle, with the peripheral body portion of the gasket 3 compressed thereagainst. Within the area of perforation or orifice 3a the normally impervious body of the liner disc comprises a diaphragm which is adapted to yield upward in re-

sponse to pressure within the bottle. The structure of the liner disc or diaphragm is so determined that, when pressure within the bottle rises to a dangerous value, the diaphragm automatically becomes perforate—it ruptures or tears in this case—and permits gas to escape through the vent or perforation 6. Thus, the normally sealed bottle is safeguarded against excessive internal pressures.

It is contemplated that many materials will be found of which to form the diaphragm 7—impregnated paper, coated metal-foil, and tissues of various sorts. The pressure at which the diaphragm ruptures may be regulated by choice of material and thickness, and in some cases the surface of the diaphragm may be weakened in the region of intended rupture, such as by means of a surface scoring 8, Fig. III.

The vent 6 in cap 1 may be provided by a pointed instrument, in such manner that pointed 20 barbs 9 remain projecting into the region 3a, into which the diaphragm bulges in response to pressure within the bottle. The points of these barbs are adapted to pierce the diaphragm pressed against them by pressure within the bottle. Fig. 25 V illustrates the diaphragm portion 1a of the gasket 7 as it is forced by pressure in the bottle upward into recess 3a and into bursting or puncturing position in the recess. In the use of the barbs 9, it is merely a question of proportioning 30 of parts and selecting of material to obtain the venting of the bottle at a pressure of given value.

We contemplate that the body of the gasket itself may include or embody the diaphragm or its equivalent. For example, the body of the gasket 35 may be recessed from its upper face downward; the recess will lie inward of the periphery of the gasket, and will extend partway through the body of the gasket, so that the relatively thin body of the gasket remaining between the bottom 40 of the recess and the lower face of the gasket comprises in effect a diaphragm. This modification is illustrated in the gasket shown in Fig. VI.

It will be understood that other modifications, refinements, and elaborations of the bottle closure described above may be made without departing from the invention defined in the appended claims. Indeed, the above disclosure will enable the engineer and artisan to embody the invention in bottle closures of other and widely 50 diversified sorts.

We claim as our invention:

1. In combination with a bottle containing liquid under gaseous pressure, a crown closure secured upon and sealing the mouth of said bottle, 55

said closure comprising a metal cap with a skirt portion for clinching the cap in assembly upon the lip of said bottle mouth, said cap including a gasket portion of compressible material peripherally compressed against said bottle lip, a recess provided in the assembled closure structure, a normally open passage for the escape of air from said recess to the outer atmosphere, and a normally impervious diaphragm portion secured 5 in gas-sealing position between said recess and the interior of said bottle, the body of said normally impervious diaphragm portion being formed of relatively inelastic, rupturable material and including a medial body portion movable 10 relatively to said compressed gasket and into diaphragm-rupturing position in said recess in response to excessive pressure within said bottle, whereby said gasket automatically ruptures and relieves pressure within the bottle. 15

20 2. In combination with a bottle containing liquid under gaseous pressure, a crown closure secured upon and sealing the mouth of said bottle, said closure comprising a metal cap with a skirt portion for clinching the cap in assembly 25 upon the lip of said bottle mouth, said cap including a gasket of compressible material peripherally compressed against said bottle lip, a recess provided in the body of said gasket, a normally open vent for the escape of air from said recess 30 to the outer atmosphere, and a normally impervious diaphragm secured in gas-sealing position between said recess and the interior of said bottle, the body of said normally impervious diaphragm being formed of relatively inelastic, rupturable 35 material and including a medial body portion movable relatively to said compressed gasket and into diaphragm-rupturing position in said recess in response to excessive pressure within said bottle, whereby said gasket automatically ruptures and relief of pressure within 40

said bottle is automatically established to the outer atmosphere.

3. A closure for sealing the mouth of a bottle whose contents are under or tend to develop pressure, said closure comprising a cap portion, a compressible gasket portion adapted to seat against the lip of said bottle mouth, a diaphragm portion cooperating with said cap and gasket portions for normally sealing the mouth of said bottle, and diaphragm-puncturing means included 10 in said closure structure, said diaphragm portion being movable relatively to said puncturing means in response to excessive internal pressure in the bottle sealed by such closure, whereby said diaphragm is automatically punctured and excessive pressure conditions relieved within the closed bottle. 15

4. In combination, a bottle, a diaphragm, cap means including a gasket for securing said diaphragm in sealed position over the mouth of said bottle, with the diaphragm positively engaged and secured over its entire periphery and subject to pressure within the bottle on one side and communicating with the open atmosphere on the other, said diaphragm comprising a normally imperforate bottle-sealing membrane formed of relatively inelastic, rupturable material, said diaphragm in normal imperforate state being adapted to yield outward against atmospheric pressure in response to normal pressures within the bottle, and to rupture and become perforate in response to excessive pressure within the bottle. 20 25

5. The structure of the next preceding claim, 30 in which said diaphragm includes a surface scoring serving more positively to effect said operation.
